HAT BLOCK CHUCK

Harry Schlesinger, Des Moines, Iowa, assignor of
one-half to Alfred F. Yoerg, Des Moines, Iowa

Application June 4, 1934, Serial No. 728,966

14 Claims. (Cl. 279—108)

The object of my invention is to provide a chuck or clutch which may be used in connection with a hat block, the chuck or clutch being comparatively simple, durable and inexpensive to manufacture.

A further object is to provide an improved chuck or clutch especially adaptable for use in connection with the hat block of a hat ironing machine, such as shown in my copending application Serial No. 576,683, filed November 23, 1931.

Still another object is to provide a chuck or clutch which can be easily and quickly operated while the machine is in motion and which is made so that it is adjustable, when used in connection with hat blocks, to blocks of various sizes by the mere manipulation of a single operating handle.

More particularly, it is my object to provide a hat block chuck comprising a hat block support and fingers resiliently pivoted thereto, in combination with a stepped cone element engageable with the fingers and movable to various positions for adjusting the fingers to different size hat blocks and to engaged or disengaged positions.

With these and other objects in view my invention consists in the construction, arrangement and combination of the various parts of my chuck or clutch, whereby the objects contemplated are attained, as hereinafter more fully set forth, pointed out in my claims, and illustrated in the accompanying drawing, in which:

Figure 1 is a side elevation of a chuck or clutch embodying my invention, showing parts broken away and other parts in section to clearly illustrate the invention.

Figure 2 is an enlarged sectional view on the line 2—2 of Figure 1 showing a slidable finger supporting element of my invention.

Figure 3 is an enlarged sectional view of the portion of Figure 1 within the circle 3, showing the association of hat block engaging fingers with a cone element of the machine.

Figure 4 is a sectional view on the line 4—4 of Figure 1.

Figure 5 is a sectional view similar to the left central portion of Figure 1 but showing the parts in a different position; and

Figure 6 is a sectional view similar to Figure 5 showing a modified form of construction.

On the accompanying drawing, I have used the reference character A to indicate generally a hat ironing machine such as the type shown in my copending application hereinbefore mentioned, but which however does not form any part of my present invention. The hat ironing machine A has a hat block shaft 10, suitably driven at a rela-

tively low speed, projecting upwardly from the machine.

My chuck or clutch includes generally a cone element C and a hat block support B. The hat block support B has a hub 12 secured to the shaft 10 by a set screw or the like 14. Spokes 16 radiate from the hub 12 and terminate in a rim 18. The spokes 16 are hollow, their bores being indicated at 20.

Slidable in the bore 20 of each spoke 16 is a pin-like element 22. It is urged toward movement in one direction by a spring 24 retained by a plug 26 and seated in sockets or bores 23 of the elements 22.

The slidable elements 22 are slotted as indicated at 28 (see Figure 2) and hat block engaging fingers 30 extend through the slots. Pivot pins 31 extend through the elements 22 and the fingers 30 for pivoting the fingers relative to the elements.

The fingers 30 extend through slots 32 and 34 of the spokes 16. The fingers thereby prevent the elements 22 from rotating in their bores. In released position, the springs 24 are free to extend the elements 22 inwardly as far as they will go. They are limited by the fingers 30 engaging shoulders 36 and 38 as in Figure 5, which tip the fingers to an open position for facilitating coaction of a hat block with the fingers, which will now be described.

At the upper ends of the fingers 30, hat block engaging elements 40 are provided, these being pivoted by pins 42 to the fingers. A hat block 44 of the ordinary type now in general use and having a hub 46 may be placed upon the support B when the fingers are in open position. The fingers can be pivoted to different relative positions to accommodate hat block hubs 46 of different sizes as illustrated by full and dotted lines in Figure 1.

For imparting pivotal movement to the fingers 30, I provide the cone element C which is of stepped character having grooves 48 of different diameters formed therein.

The lower ends 30a of the fingers 30 are hooked as best shown in Figure 3 to enter the various grooves 48.

The cone element C is preferably free to rotate either with or relative to the shaft 10 and is provided with an annular groove 50. An operating lever 52 is pivoted at 54 and has a handle portion 56. The lever 52 is of forked construction, straddling the lower portion of the cone element C and has a pair of pins 58 extending into the groove 50 so that swinging movement of the lever 52 about the pivot 54 will impart sliding move-

ment to the cone element C. The pins 58 are preferably provided with rollers in the groove 50.

Although I have illustrated my invention in connection with a hat block, it is obvious that

5 it can be used as a clutch for rotating any element simultaneously with a shaft or disconnecting the two with relation to each other to stop such rotation. For instance, the shaft 10 may be considered a drive shaft and the hub 46 may 10 be considered a driven element on the shaft, such as a pulley or the like, so that the handle 56 can be manipulated for driving the pulley with the drive shaft or declutching it relative thereto.

15 The illustration on my patent drawing is merely by way of example and it is to be understood that my claims are not to be construed as limited to a chuck or clutch useable with hat blocks only.

20 In Figure 6, I show a modified form of construction in which parts similar to the parts in the preceding figures bear the same reference numerals with the addition of the distinguishing characteristic b. In addition to these parts, I 25 provide a head element 60 for the spring 24b which has a shank 62 extending some distance into the spring. The head element 60 is adapted to bear against a face 64 of the finger 30b, thus tending to tip it to the released position of Figure 5 without, however, engaging the shoulders 36 and 38.

25 The head element 60 is retained in alignment by snugly fitting in the spring 24b and the spring in turn snugly fitting the bore 23b of the slideable 30 element 22b. The plug 26b is of recessed construction to provide increased length for the spring so that its tension does not vary so greatly when adjusting the ends 30a of the fingers 30b from one groove 48 to another. The bore 23b 40 in Figure 6 is of course much deeper than the bore 23 of Figure 2 so that the head 60 can contact with the face 64 of the finger 30b.

Practical operation

45 In the operation of my device, the support B, of course, rotates with the shaft 10 and the hat block 44 can be placed on the support while the cone element C is in its raised dotted line position of Figure 1, in which position the fingers 50 30 are open as shown in Figure 5.

The lever 52 may then be lowered from the dotted line position as far as it will move downwardly without excessive pressure being exerted on the handle 56. This will first cause the 55 upper ends of the fingers 30 to swing inwardly, causing the elements 40 to engage and grip the hub 46, whereupon slight further movement of the cone element will slide the elements 22 outwardly against the tension of the springs 24. 60 The hat block 44 is then gripped under resilient tension and rotates with the shaft 10 so that the surface of a hat thereon can be cleaned, brushed, or ironed by the iron shown in my copending application.

65 The cone element C is stepped so that it is adjustable by movement of the operating handle 56 to various sizes of hat block hubs. The spring tension 24 is provided so as to compensate for slight differences in diameters which could not 70 be taken care of by the steps of the cone C. The springs also provide predetermined tension of the elements 40 on the hat block 44 and in conjunction with the shoulders 36 and 38, serve for the purpose of opening the fingers when the 75 cone is raised.

In the use of the construction shown in Figure 6, the handle 56 when fully raised will permit the slideable element 22b to strike the bottom of the bore in the spoke 16b indicated at 66.

The finger 30b will then be held in the released position illustrated by the surface 64 being constrained by the spring 24b to contact with the full height of the head 60. The first downward movement of the handle 56 will swing the lower end of the finger 30b outwardly and the upper end inwardly until the element 40b engages the hat block hub, whereafter further movement will slide the element 22b outwardly as in the operation of the device illustrated in the preceding figures. 15

Some changes may be made in the construction and arrangement of the parts of my device without departing from the real spirit and purpose of my invention, and it is my intention to cover by my claims, any modified forms of structure or use of mechanical equivalents, which may be reasonably included within their scope. 20

I claim as my invention:—

1. In a chuck, a shaft, a driving element thereon, fingers pivoted to said driving element, the pivotal mounting for each finger being movable relative to said driving element and a cone element on said shaft and slideable relative thereto, said cone element being engageable with said fingers to impart pivotal movement thereto to cause the fingers to engage a driven element, said pivotal mounting being spring urged toward the driven element. 25

2. In a chuck, a shaft, a driving element thereon, fingers pivoted to said driving element, the pivotal mounting for each finger being movable relative to said driving element and a stepped cone element on said shaft and slideable relative thereto, said cone element being engageable with said fingers to impart pivotal movement thereto to cause the fingers to engage a driven element, said pivotal mounting being spring urged toward the driven element. 40

3. In a chuck, a shaft, a driving element thereon, fingers pivoted to said driving element, the pivotal mounting for each finger comprising a slideable slotted pin, the finger extending through the slot of the pin and a pivot pin extending through the slideable pin and the finger and a cone element on said shaft and slideable relative thereto, said cone element being engageable with said fingers to impart pivotal movement thereto to cause the fingers to engage a driven element and means urging said slideable pins and thereby said fingers toward said driven element and cone. 50

4. In a chuck, a shaft, a driving element thereon, fingers pivoted to said driving element, the pivotal mounting for each finger comprising a slideable slotted pin, the finger extending through the slot of the pin and a pivot pin extending through the slideable pin and the finger, spring means to urge the slideable pins toward a driven element and a cone element on said shaft and slideable relative thereto, said cone element being engageable with said fingers to impart pivotal movement thereto to cause the fingers to engage said driven element. 60

5. In a chuck, a shaft, a driving element thereon, fingers pivoted to said driving element, the pivotal mounting for each finger comprising a slideable slotted pin, the finger extending through the slot of the pin and a pivot pin extending through the slideable pin and the finger, spring means to urge the slideable pins toward a driven element, shoulders for said fingers to engage when 70

5 said spring means is free to cause such engagement, said shoulders being arranged for causing the fingers to assume an open position with respect to the driven element and a cone element 5 on said shaft and slidable relative thereto, said cone element being engageable with said fingers to impart pivotal movement thereto to cause the fingers to engage said driven element.

6. In a chuck, a shaft, a driving element there- 10 on, fingers pivoted to said driving element, the pivotal mounting for each finger comprising a slidable slotted pin, the finger extending through the slot of the pin and a pivot pin extending through the slidable pin and the finger and a 15 stepped cone element on said shaft and slidable relative thereto, said cone element being engageable with said fingers to impart pivotal movement thereto to cause the fingers to engage a driven element and means urging said slidable 20 pins and thereby said fingers toward said driven element and cone.

7. In a chuck, a shaft, a driving element there- 25 on, fingers pivoted to said driving element, the pivotal mounting for each finger comprising a slidable slotted pin, the finger extending through the slot of the pin and a pivot pin extending through the slidable pin and the finger, spring means to urge the slidable pins toward a driven element and a stepped cone element on said shaft 30 and slidable relative thereto, said cone element being engageable with said fingers to impart pivotal movement thereto to cause the fingers to engage said driven element.

8. In a chuck, a shaft, a driving element there- 35 on, fingers pivoted to said driving element, the pivotal mounting for each finger comprising a slidable slotted pin, the finger extending through the slot of the pin and a pivot pin extending through the slidable pin and the finger, spring means to urge the slidable pins toward a driven element, shoulders for said fingers to engage when said spring means is free to cause such engagement, said shoulders being arranged for causing the fingers to assume an open position with respect to the driven element and a stepped cone 45 element on said shaft and slidable relative thereto, said cone element being engageable with said fingers to impart pivotal movement thereto to cause the fingers to engage said driven element.

50 9. A chuck comprising a shaft, a ring-shaped driving element thereon having a hub and spokes, said spokes being hollow, slidable elements in said spokes, said spokes and slidable elements being slotted, driven element engaging fingers extending through the slots thereof and pivoted to said 55 slidable elements, spring means engaging said slidable elements and tending to force them toward a driven element when supported on said driving element and a cone element on said shaft slidable relative thereto and engageable with said fingers to impart pivotal movement thereto to cause interengagement between the fingers and the driven element.

60 10. A chuck comprising a shaft, a ring-shaped driving element thereon having a hub and spokes, said spokes being hollow, slidable elements in said spokes, said spokes and slidable elements being slotted, driven element engaging fingers extending through the slots thereof and pivoted to said

slidable elements, spring means engaging said slidable elements and tending to force them toward a driven element when supported on said driving element and a stepped cone element on said shaft slidable relative thereto and engageable 5 with said fingers to impart pivotal movement thereto to cause interengagement between the fingers and the driven element.

11. A chuck comprising a shaft, a ring-shaped driving element having a hub and spokes, said 10 spokes being hollow, slidable elements in said spokes, said spokes and slidable elements being slotted, driven element engaging fingers extending through the slots thereof and pivoted to said slidable elements, spring means engaging said slidable 15 elements and tending to force them toward a driven element when supported on said driving element, a cone element on said shaft slidable relative thereto and engageable with said fingers to impart pivotal movement thereto to cause interengagement between the fingers and the driven element and shoulders for said fingers to engage when said cone element is in released position, said spring means causing such engagement and said shoulders being so associated with the fingers 20 that they tip the fingers to an open position for receiving said driven element.

12. A chuck comprising a shaft, a ring-shaped driving element thereon having a hub and spokes, said spokes being hollow, slidable elements in said 30 spokes, said spokes and slidable elements being slotted, driven element engaging fingers extending through the slots thereof and pivoted to said slidable elements, driven element engaging elements pivoted to said fingers, spring means engag- 35 ing said slidable elements and tending to force them toward a driven element when supported on said driving element and a cone element on said shaft slidable relative thereto and engageable with said fingers to impart pivotal movement 40 thereto to cause interengagement between the fingers and the driven element.

13. In a chuck, a shaft, a driving element there- 45 on, fingers pivoted to said driving element, the pivotal mounting for each finger comprising a slidable slotted pin, the finger extending through the slot of the pin and a pivot pin extending through the slidable pin and the finger, spring means to urge the slidable pins toward a driven element, shoulders on said fingers for said spring 50 means to engage, said shoulders being arranged for causing the fingers to assume an open position with respect to the driven element and a cone element on said shaft and slidable relative thereto, said cone element being engageable with said 55 fingers to impart pivotal movement thereto to cause the fingers to engage said driven element.

14. In a chuck, a shaft, a driving element there- 60 on, fingers pivoted to said driving element, the pivotal mounting for each finger comprising a slid- able slotted pin, the finger extending through the slot of the pin and a pivot pin extending through the slidable pin and the finger, spring means to urge the slidable pins toward a driven element and for tipping the fingers to released position 65 when the fingers are free and a cone element on said shaft, slidable relative thereto and engageable with said fingers.

HARRY SCHLESINGER.
